(57) **CLAIM**

The ornamental design for a distribution transformer monitor, as shown and described.

DESCRIPTION

FIG. 1 is a front perspective view of a distribution transformer monitor, showing our new design;

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

In the drawings, the broken lines illustrate portions of the distribution transformer monitor that forms no part of the claimed design. Shading lines shown in the drawings are intended to represent approximate three-dimensional contours of the design and are not intended to indicate surface decoration.
